Primary Examiner — Cynthia R Underwood*(74) Attorney, Agent, or Firm* — Lee & Hayes, P.C.(57) **CLAIM**

The ornamental design for an electronic device cover, as shown and described.

DESCRIPTION

FIG. 1 is a front perspective view of an electronic device cover;

FIG. 2 is a back perspective view thereof;

FIG. 3 is a front view thereof;

FIG. 4 is a back view thereof;

FIG. 5 is top view thereof;

FIG. 6 is a bottom view thereof;

FIG. 7 is a cross-sectional view taken along the line 7-7 shown in of FIG. 3;

FIG. 8 is a left-side view thereof; and,

FIG. 9 is a right-side view thereof.

The broken lines depict portions of the electronic device cover that form no part of the claimed design. The dot-dashed broken lines represent boundaries of the claimed electronic device cover and form no part of the claimed design.
